SEPARABLE SLIDE FASTENER

Irving Greenberg, Union City, N. J.

Application May 24, 1933, Serial No. 672,591

4 Claims. (Cl. 2—128)

This invention relates to slide fasteners of the separable type, particularly as used on reversible garments or other reversible articles.

The terminal elements at the ends of these fasteners are usually of the pin and socket type, requiring that one be slipped over the other in a certain definite direction, in separating and in connecting the fastener. This means that when the article is faced one way the pin element will 10 be at one side of the fastener seam and that when the article is reversed, this same pin element will be at the opposite side of the fastener seam. Unless therefore, and which would be quite unusual, the user remembers exactly on 15 which side the pin element, for example, is located when the article is faced in opposite directions, he must ascertain, by experiment or close inspection, on which side of the seam the pin element is located, before knowing which way 20 to shift the parts to effect the engagement or disengagement of the same.

The objects of the invention are to avoid the difficulties mentioned and to enable the quick and instant engaging and disengaging of the fastener parts without any need of studying or experimenting to find which way the members must be 25 put together or taken apart.

Other desirable objects and features of the invention will appear as the specification proceeds. 30 The drawing accompanying and forming part of the specification illustrates the invention as embodied in a number of different practical forms and it is to be understood that the actual physical structure may be further modified, all 35 within the true intent and broad scope of the invention.

Fig. 1 is a perspective view of a form of the invention as incorporated in a reversible jacket construction, illustrating a method of utilizing 40 the invention in effecting the engagement or the separation of the terminals of the slide fastening.

Fig. 2 is an enlarged broken detail, illustrating the terminally identified parts shown in Fig. 1.

Figs. 3 and 4 are broken end views of the parts 45 shown in Fig. 2, in the separated and connected relations, the latter view illustrating a modification in the form of the fastener member identification.

Figs. 5 and 6 are broken face views of another 50 form of the invention in the two relatively reversed relations.

Fig. 7 is a similar view of a further modification of the invention.

The fastener shown comprises the cooperating 55 sets of fastener elements 9, 10, on stringer tapes

11, 12, secured in the opposing edge portions of a reversible garment 13, and designed to be interlocked and reversed by slider 14.

At the end of the fastener are the cooperating pin and socket terminals 15, 16, which must be 5 lifted, one out of the other, before the fastener can be separated and, conversely must be set one within the other, before the fastener can again be closed.

When the garment is faced one way, the pin 10 member, for example, will be disposed at one side of the fastener seam and, when the garment is reversed, this same element will be disposed at the opposite side of the seam.

It is difficult to remember and, an annoyance 15 to endeavor to recall at which side of the seam the one element will be when the garment is faced in either one direction and, as these terminal members are usually at the waist line, in a position 20 where they can not be quickly or easily inspected, it has been frequently the custom simply to experiment by trying to slide one member over the other, until the proper relation is found.

In the present invention, one or the other, or 25 both terminal members are identified and distinguished, so that the user is informed which is which and knows at once which way to slide the members together or to separate them.

In the several embodiments illustrated, the pin 30 member is the one which is identified and distinguished.

In the first form shown, Figs. 1 to 3, this distinction is effected by the provision of specially shaped members or markers on the pin carrying member of the fastener, in this case, 35 square shaped buttons 17, at both faces of this member, adjacent the pin and in position to be naturally engaged by the fingers grasping this member of the fastener for engaging or disengaging purposes. These buttons, in practice may be in the nature of specially-shaped rivet heads, secured through the shank portion 18 of the pin element by tubular rivet studs 19. These unusually shaped buttons or rivet heads are readily and 40 immediately distinguishable from ordinary circular rivet heads, such as indicated at 20, which may be in use on the opposite side member of the fastener.

To make the distinction more prominent, the 45 markers 17 may be coned or pointed as indicated at 21, Fig. 4.

In Figs. 5 and 6, the distinguishing markers 17 are shown as conspicuously colored at 22, which 50 special feature suffices when the marker is in plain position to be seen.

In another form of the invention shown in Fig. 7, the marking is effected by location as well as by form of the marker. Thus in this view, the marker 17 is shown set back a further distance 5 from the seam than the rivet fastenings 20, at the opposite side of the seam and it has a symbol such as a letter 23, sunk in the face of the same, providing a degree of roughness and a mark recognizable by the feel of the fingers.

10 The slide fastener illustrated is of the double locking reversible type covered in Patents 1,903,-415 and 1,955,288, in which the pull member 24 is reversible over opposite sides of the slide to lock the slide at either side of the fastener, as, 15 in the illustration, by a lug or prong 25, on the pull adapted to extend through openings 26, in the opposite sides of the slide into engagement with the fastener elements. When the fastener members are to be separated, this slide is brought 20 down to the end of the fastener as in Fig. 2 and then when the lock is released, as shown, the pin member can be withdrawn up through the socket and the slide, or conversely can be inserted down through the slide and into the socket. In these 25 movements of disconnecting and connecting the parts, it is convenient usually to hold one part and to lift up or push down the other part. Usually the socket side of the fastener will be held and the pin side of the fastener be lifted or lowered 30 for disconnecting or connecting purposes. This is a reason for placing the distinguishing means or markers on the pin side of the fastener, for the user then knows that the side with the markers, irrespective which way the garment or 35 article is faced, is the side which is to be pulled up for disconnecting or lowered for connecting.

The distinguishing or marking means, in cases where the final connecting elements of the fastener are more or less out of sight as by being 40 obscured by the overhanging blouse portion of a garment as in Fig. 1, preferably will be quite distinctive and instantly recognizable by sense of touch. In such cases, pointed, roughened, sharp cornered or otherwise sharply defined markers 45 may be used, which will be instantly recognizable even with gloved hands.

While the identifying markers have been illustrated as in each case as associated with the pin element, it will be clear that the same might be 50 associated with the opposite or socket element of the fastener and in practically the same way, as this element also has a mounting tab portion 18' through which the marker buttons could be riveted or otherwise suitably fastened. The co-operating terminal parts of the fastener have been referred to as pin and socket elements, as a matter of convenience in description. Other terms have been similarly used in a descriptive 55 rather than in a limiting sense, and are to be so understood, except possibly for limitations such as might be imposed by the prior state of the art. To make the markers stand out more prominently, the rivet heads or buttons 20, at the side of the seam opposite the markers may be omitted entirely or be much smaller or otherwise made less prominent.

What is claimed is:

1. In combination, a reversible garment having parts separable to permit reversal of the garment, 70 a reversible separable slide fastener for connecting said separable garment parts and including fastener members on opposite edge portions of the separable parts of said garment, said opposed

fastener members terminating in companion pin and socket elements engageable and separable in the two relatively reversed positions of the garment and means associated with the fastener for distinguishing and identifying the separable edge portion carrying the pin member from the other edge portion carrying the socket member of the fastener and thereby enabling the parts of the fastener to be engaged in either of the relatively reversed relations of the garment without searching to locate said pin and socket members. 10

2. In combination, a reversible garment having parts separable to permit reversal of the garment, a reversible separable slide fastener for connecting said separable garment parts and including 15 fastener members on opposite edge portions of the separable parts of said garment, said opposed fastener members terminating in companion pin and socket elements engageable and separable in the two relatively reversed positions of the garment, means associated with the fastener for distinguishing and identifying the separable edge portion carrying the pin member from the other edge portion carrying the socket member of the fastener and thereby enabling the parts of the 20 fastener to be engaged in either of the relatively reversed relations of the garment without searching to locate said pin and socket members, said distinguishing means including indicating markers on one of the separable members of the fastener and exposed at the opposite faces of the 25 garment.

3. In combination, a blouse structure having a close fitting waist band and open at the front to enable complete reversal of the garment, co-operating fastener members on the separable front edges of the garment and including separable companion terminal pin and socket elements at the waist band ends of said cooperating fastener members, a slide for engaging and releasing said fastener members, a pull for shifting said slide in opposite directions and reversible for effecting actuation of the slide in either of the relatively reversed relations of the garment and means on said waist band at one side of said front opening for denoting which of the separable terminal elements is located at that side and thereby the movement necessary to effect the engagement with or separation of that element from the companion terminal element at the 30 other side of the waist band opening. 40

4. In combination, a garment having separable portions, a slide fastener comprising companion separable fastener members on said separable portions of said garment and provided with co-operating pin and socket elements at the opposed 45 ends of the same engageable and separable by relatively longitudinal movements of the ends of said separable portions of the garment and an identifying marker on one of said separable end portions of the garment for distinguishing the separable edge portion carrying the pin member from the other edge portion carrying the socket member of the fastener, said identifying marker being set back from the fastener member at the edge of that portion to definitely inform which edge portion is to be lifted or lowered with respect to the other edge portion for coupling or uncoupling the fastener and without interfering with the actual engagement or disengagement of 50 said fastener members. 60

IRVING GREENBERG.
